UNITED STATES PATENT OFFICE.

EDWARD YOCKEY, OF MILWAUKEE, WISCONSIN.

DESIGN FOR A TIRE.

57,758.

Specification for Design.

Patented Apr. 26, 1921.

Application filed March 31, 1920. Serial No. 370,343. Term of patent 7 years.

To all whom it may concern:

Be it known that I, EDWARD YOCKEY, a citizen of the United States of America, residing at Milwaukee, in the county of Milwaukee and State of Wisconsin, have invented a new, original, and ornamental Design for Tires, of which the following is a specification, reference being had to the accompanying drawing, forming part thereof.

The figure is a plan view of a portion of a tire tread, showing my new design.

I claim:

The ornamental design for a tire as shown.

EDWARD YOCKEY.
